UNITED STATES PATENT OFFICE.

GEORGE A. BAUSMAN, OF MINNEAPOLIS, MINNESOTA.

ADJUSTABLE SCREEN.

SPECIFICATION forming part of Letters Patent No. 549,892, dated November 19, 1895.

Application filed August 8, 1895. Serial No. 558,688. (No model.)

To all whom it may concern:

Be it known that I, GEORGE A. BAUSMAN, a citizen of the United States, residing at Minneapolis, in the county of Hennepin and State 5 of Minnesota, have invented certain new and useful Improvements in Adjustable Screens; and I do hereby declare the following to be a full, clear, and exact description of the invention, such as will enable others skilled in 10 the art to which it appertains to make and use the same.

My invention relates to adjustable screens for windows, &c., and has for its especial object to provide an improved construction for 15 the outside sash whereby the screen may be readily adapted to different sizes of windows and which shall at the same time be fly-tight and be cheap to make.

To these ends my invention consists of the 20 novel features hereinafter described, and defined in the claims.

The invention is illustrated in the accompanying drawings, therein like letters referring to like parts.

Figure 1 is a perspective view of my improved screen detached with some parts broken away, the sections of the outside sash being shown as extended sidewise and closed together endwise of the window, or in the vertical direction. Fig. 2 is a horizontal section on the line x x of Fig. 1. Fig. 3 is a cross-section, looking toward the left, on the line x' x' of Figs. 1 and 2. Fig. 4 is a similar view on the line x^2 x^2 of Figs. 1 and 2. Fig. 5 is a similar view on the line x^3 x^3 of Figs. 1 and 2. Fig. 6 is a perspective view edgewise of the sash with some parts broken away and the sash-sections pulled apart. Fig. 7 is an inside end view of the left-hand sash-section 35 shown in Fig. 6. Fig. 8 is a similar view of the right-hand sash-section shown in Fig. 6. Fig. 9 is a horizontal section on the line x^4 x^4 of Fig. 7, and Fig. 10 is a similar view on the line x^5 x^5 of Fig. 8.

45 a a' represent the screen proper, of which parts a is the wire cloth or netting, and a' the non-adjustable rigid frame of the screen. The said screen a a' is mounted within a suitable seat b of the outside adjustable sash, 50 which is constructed in corner sections, the arms of which unite by telescoping tongue and tongue-seat joints, so arranged as to be

fly-tight at all points of the adjustment. The said corner sections are each composed of spacing-strips c and body-pieces c' united by 55 the said spacing-strip c and inside liners c^2 . The said spacing-strips c form the marginal or outside wall and the body-pieces c' the side walls of the seat b , in which is mounted the rigid frame a' of the screen proper. 60

For convenience in describing the peculiar tongue and tongue-seat telescoping-joint, by which the sash-sections unite, one of the arms of each section will be called the "male" arm and be represented by the numeral 1, and the 65 other arm of each corner section will be called the "female" arm and be represented by the numeral 2, and, of course, it will be understood that the male arm of any given section co-operates with the female arm of the opposite 70 section.

The body-pieces c' of each of the arms 1 and 2 is provided with a pair of tongues c^3 c^4 and a pair of tongue-seats c^5 and c^6 . On the male arms 1 the tongues c^4 are flush with 75 the inner faces of the said body-pieces c' , and on the female arms 2 the tongues c^4 are flush with the outside surfaces of the body-pieces c' . The tongue-seats c^5 are on both the male and female arms between the pairs of tongues c^3 and c^4 ; but the seat c^6 in the case of the male arm 1 is formed by rabbeting the outer surface of the body-piece, and in case of the female arm the corresponding seat c^6 is formed by rabbeting the inside surface of the body- 80 piece. The spacing-strips c on the male arms are of greater length than on the female arm; or otherwise stated the spacing-strip c on the male arm extends to the ends of the tongue c^4 , while on the female arm the said spacing- 85 strip stops at the outer end of the recess formed by the rabbeted seats c^6 . This arrangement, of course, provides a seat or groove c^7 at the top of the female arm in which the strip c of the male arm may telescope. The 90 inside liners c^2 extend to the outer ends of the rabbeted seats c^6 on the male arms, and to the inner ends of the tongues c^4 on the female arms. 95

The body-pieces c' are of the requisite width 100 relative to the spacing-strips c to afford the seat b of the desired width for the desired range of adjustment of the sash in respect to the screen proper.

From the foregoing description of the parts of the telescoping-joints it must be obvious that the male and female arms of the corner sections will unite, as shown best in Figs. 1 and 2 of the drawings, with the tongues c^3 engaging and telescoping in the mortise-like seats c^5 , the tongues c^4 engaging and lapping the tongues c^3 in the rabbeted seats c^6 , and the spacing-strip c on the male arm telescoping in the seat c^7 of the female arm. With this peculiar form of tongue and tongue-seat telescoping-joint, uniting the male and female arms of the opposite corner sections, it is obvious that the outside sash is adjustable in either or both directions at will, and that in all the adjustments no transverse or other open passage will be afforded whereby a fly or other insect could enter through the joint into the interior of the building.

The tongues c^3 , engaging the mortise-like seats c^5 , binds the arms together against any tilting action edgewise of the sash, and the tongues c^4 , lapping the tongues c^3 on the rabbeted seats c^6 , serve to lap the joint at both its outside and inside faces up to the top margin of the sash, or, in other words, to a point flush with the spacing-strip c . The inside liners c^2 serve as stops to limit the outward movement of the sash-section by the engagement which would occur between the said liners c^2 and the inside margins of the screen-frame a' , and on the female arms the said liners c^2 also serve to close the openings, which would otherwise occur at the netting-edges of the rabbeted seats c^6 on the female arms when the sections are pulled apart, and thereby close the passage, which might otherwise occur through the said rabbeted seat c^6 and the

groove or seat c^7 for the spacing-strip. Hence, when the screen-sash is in position under the window-sash, as all the top openings will be closed by the sash of the window, and all the other outside openings will be closed by the window-casing, it follows that the telescoping joints between the arms of the opposite sections will be fly or insect tight.

Inasmuch as the tongues and tongue-seats necessary for the telescoping joints herein described may be readily formed by the ordinary wood-working machinery on the body pieces c' of the frame-section, it follows that in virtue of this invention a two-way adjustable sash can be readily made at small cost.

What I claim, and desire to secure by Letters Patent of the United States, is as follows:

1. The combination with a screen, of an adjustable sash for the same, composed of corner sections, each arm of which is made up of spacing strips c and body pieces c' having the tongues c^3 and tongue seats $c^5 c^6$, cooperating to unite opposite sections with telescoping fly-tight joints, substantially as described.

2. The combination with the screen $a a'$, of the adjustable sash for the same, comprising corner sections, each composed of the spacing strip c , the body pieces c' having the tongues $c^3 c^4$ and the tongue-seats $c^5 c^6$, arranged as described, and the inside liners c^2 , all cooperating substantially as and for the purposes set forth.

In testimony whereof I affix my signature in presence of two witnesses.

GEORGE A. BAUSMAN.
